application Jan. 2, 1974, Ser. No. 429,789

Term of patent 14 years

Int. Cl. D10—04

U.S. Cl. D10—62

FIG. 1 is a left front perspective view of a drafting instrument showing my new design, the bottom thereof being generally plain;

FIG. 2 is a left front perspective view of a modified form of my new design of FIG. 1 wherein the sides have different angulation;

FIG. 3 is a typical right side elevational view of either FIG. 1 or FIG. 2.

This is a divisional application of Ser. No. 208,511, filed Dec. 15, 1971, now Design Patent D. 232,051; which is in turn a continuation-in-part of Ser. No. 160,234, filed July 6, 1971, now Design Pat. D. 226,226.

I claim:

The ornamental design for a drafting instrument, as shown and described.
